George Peyrot, New York, N. Y.

Application May 4, 1944, Serial No. 113,457

Term of patent 7 years

(Cl. D45—4)

To all whom it may concern:

Be it known, that I, George Peyrot, a citizen of the United States, residing in New York city in the county of New York and State of New York, have invented a new, original, and ornamental Design for a Combined Wrist Watch and Bracelet, of which the following is a specification, reference being had to the accompanying drawing, forming part thereof.

Fig. 1 is a top plan view of a combined wrist watch and bracelet with the watch member in an open position,

Fig. 2 is a top plan view, thereof with the watch member in closed position, and

Fig. 3 is a side view of the combined wrist watch and bracelet as shown in Fig. 2.

I claim:

The ornamental design for a combined wrist watch and bracelet, substantially as shown.

GEORGE PEYROT.
